UNITED STATES PATENT OFFICE.

JOHN MONTGOMERY, OF TORONTO, ONTARIO, CANADA.

BOX-CAR.

1,263,095.

Specification of Letters Patent. Patented Apr. 16, 1918.

Application filed February 17, 1917. Serial No. 149,276.

To all whom it may concern:

Be it known that I, JOHN MONTGOMERY, of the city of Toronto, in the county of York, Province of Ontario, and Dominion of Canada, have invented certain new and useful Improvements in Box-Cars, and do hereby declare that the following is a full, clear, and exact description of the same.

In railroad operation, box cars are required to carry all kinds of package and loose merchandise, loaded and discharged with greater or less difficulty, usually without regard for the property of the railway corporation or the requirements of the subsequent user.

As an instance of the above, a box car may be used for the carriage of: (a) steel rails, water pipes, large timbers, lumber, and the like, which, owing to their length, are loaded and discharged through a small door placed at the end of the car; (b) machines and large crates which, owing to their weight and bulk, are loaded and discharged through the side doors; (c) grain or other loose merchandise, for the loading or discharge of which, the operating conditions may require the use of either the side or end doors or both; and it has been ascertained in the field of actual use, in the case of both inside and outside doors, that when fittings, no matter how small, even the head of a bolt or coach screw, are attached to the door post so as to obstruct the total width of the door opening, or, lessen the width of the car, by a fraction of an inch, the car will not be in operation many days before such fittings are broken off, either during the loading and unloading of the freight, or by a shipper requiring the full width of the door opening, or the full width of the car, and the car is thus disabled for the use of a subsequent shipper.

Inside doors, such as ordinarily used for grain-carrying purposes, heretofore stored, when not in use, beneath the car roof, are now impractical, not only for the above reasons, but also on account of their weight and size, and, the height of the car; and outside doors are often blocked, by the load shifting in transit and binding against them, or by part of the load becoming so wedged between the door and the balance of the

load, or between the door and the car body, as to prevent the sliding movement of the door when an effort is made to open it; and the car posts, are not only injured during, the carriage, and, the loading and unloading, of the freight, but often become warped or bent, owing to the condition of the wood during the construction of the car, and under such conditions a grain door cannot, as ordinarily built, be made to fit tightly against the door posts.

To overcome these and other difficulties in connection with the use of car doors, is the object of the present invention, which is attained, by constructing the door to operate on the ordinary outside sliding principle, thus eliminating the use of fittings which would lessen the width of the door opening or the inside width of the car, by providing means to establish a grain-tight joint between the door opening and door, when the latter is closed and locked, so that when the car is employed for grain-carrying purposes, there will be no leakage between the door and the car body, and to so arrange this means that when unlocked the door will be permitted to swing outward clear of any obstructions which may become wedged between the load and the door or between the door and the car body.

Referring to the drawings:

Figure 1, is a fragmentary side elevation of a car and car door; 85

Fig. 2, is a fragmentary horizontal section on the line $a-a$, Fig. 1;

Fig. 3, is a fragmentary sectional plan of one of the door posts and car door;

Fig. 4, is a detail sectional elevation on the line $b'-b'$, Fig. 3;

Fig. 5, is a detail sectional elevation, at right angles to Fig. 4, of the parts shown in that figure;

Fig. 6, is a front elevation of the small door at the bottom of the main car door;

Fig. 7 is a horizontal section on the line $c-c$, Fig. 6;

Fig. 8, is a vertical section on the line $d-d$, Fig. 6; and,

Fig. 9, is a horizontal section through the small door at the top of the main car door.

A represents the top of the floor inside the car; B represents the car body, B' repre-

sents a door way in the car body, C represents a stock sliding door track secured to the outside of the car body, above the door way; D represents stock door hangers; E represents a car door, suspended by the door hangers from the track; and 2 and 3 represent the car posts.

From the track C and the door hangers D, the car door is suspended to slide, as usual, close to the side of the car body until the door opening is closed or exposed, as the case may be; this movement in no way being interfered with by any of the additional features, hereinafter described, and no material change being made in the general construction, other than that the door has extra weight and is built stronger than formerly.

On both edges and the bottom of the door, strong metal sliding plates 8, 8^a and 8^b are securely but slidably fastened, by means of special neck bolts 10 passing through the elongated slots 9, and made up tight by means of nuts 10^a, blind-mortised into the frame of the door, these fastenings occurring at intervals in the length of the plate. Close to each of the slots 9 is placed a metal rib 13, these ribs being securely riveted to the plates 8, 8^a and 8^b. Each rib 13 has an offset 13^a, as shown in Fig. 3, terminating in a wedge-shaped lug 14, the offsets 13^a permitting the lugs 14 to pass freely into holes 21 in the plates 19, 19^a, 19^b; see Figs. 3, 4, and 5. Each neck bolt 10 has a neck part 11 larger than the stem, and slightly less in diameter than the width of slot 9, and a head 10^b larger than the slot to overlap the sides thereof.

In assembling the parts, the shoulder 11^a of the neck part comes to rest on a washer 12, and the bolt can thus be made up tight, without causing the bolt head to bind or pinch the sliding plate 8.

Coöperating with plates 8, 8^a, and 8^b are stationary metal plates 19, 19^a and 19^b, respectively, rabbeted into and secured to the car posts 2 and 3 and into the sill b just below the door opening, these plates 19, 19^a and 19^b being securely bolted in position with plow bolts 20, see Figs. 3, 4 and 5.

A section of these plates, 19, 19^a, 19^b, shows a lengthwise groove 25 and flange 25^a, see Fig. 3, each flange having rectangular holes 21, see Fig. 4, with a wedge-shaped lip 22 projecting into one corner of each hole. A mortise is cut into the post and sill opposite these holes of sufficient size so that the lug 14 can move freely through the hole 21. The plates 8 and 8^a have a length about equal to the height, and the plate 8^b has a length about equal to the width of the door, the plates 19, 19^a, 19^b corresponding in length to the plates 8, 8^a, 8^b respectively.

The plates 8, 8^a, 8^b, are actuated by means of a lever 15 and bell cranks 17 connected

by links 16 16^a, the parts 15 and 17 being pivoted to the car door by strong bolts 10^b similar to the neck bolts 10.

To draw off that part of the car contents lying against the inside of the car door and thus prevent waste when unloading at sidings and warehouses, the main car door E near the bottom thereof, is formed with a small door opening 1^a to discharge into a spout, hopper, or the like, and surrounding the door opening 1^a, is a metal frame 28, bored for bolts 28^b by which it is fastened to the car door.

At one side of the metal frame 28 are hinge lugs 28^a, and at the opposite side are locking lugs 28^b. On the outer side of the frame 28, is a swing door 29, provided with a hinge member 29^a to enter between the hinge lugs 28^a, the lugs 28^a and 29^a being bored for the hinge pin 29^b.

The swing door 29 is provided with a lug 29^c to enter between the locking lugs 28^b, the lugs 28^b and 29^c being bored for the locking pin 29^d, by which the door is maintained in its closed position.

The inner face of the door 29 is formed with a flange 29^e parallel with its edges, and this flange enters a corresponding groove 28^d in the metal frame 28, the purpose of the flange and groove being to prevent a leakage of grain between the swing door 29 and the frame 28 when the swing door is closed and locked.

For loading the car to its full capacity and to provide an entrance for grain spouts, inspectors, shovelers and the like, the top of the main car door E is formed with a door opening 1^b, and surrounding the inner side of the door opening, is a metal frame 32^e having a metal tongue 32.

Hinged to the car door to close the door opening 1^b, is a swing door 32^b, having a groove 32^c to receive the metal tongue 32, the swing door 32^b being provided with the usual stock hinges 32^d and lock 32^e.

Operation.

When the lever 15 is at Y, the door is securely closed and ready for the seal. When the lever is moved from Y to Z, the door is released, and may be operated as an ordinary sliding door.

If the car is to be used for grain or other loose merchandise, the door may be moved to close the door opening, and the lever 15 swung from Z to Y, and the sealing pin 23 may be inserted through the sealing clevis 27 and sealed with a standard seal, to hold the lever in that position.

By moving the lever 15 from Z to Y, an important operation takes place, that is to say, the three sliding plates 8, 8^a, 8^b are actuated simultaneously. As the movements of the three plates are identical, the movement of one is all that it is necessary to

describe; namely, the plate 8, shown on the right side of the door, but in the reverse position to that shown in Figs. 1, 4, and 5. The position of lever 15 would be 5 at Z and plate 8 would be at its highest point; the slot 9 would show nearly its full length above bolt 10, and the lug 14 would be in position 14^a.

During the first stage of the movement 10 from Z to Y, the lever 15 forces plate 8 downward and inward, the inward movement being caused by the shape of the slot 9, shown in Fig. 5 very little stress being required on the lever 15 until the angle in 15 the slot reaches the bolt, on account of the freedom from friction of the plate 8 and lugs 14, as previously described.

When plate 8 has moved to bring the angle of the slot 9 to the bolt 10, the wedge-shaped lug 14 has moved from the starting position 14^a to the intermediate position 14^b, and the inside edge of the plate 8 has entered the groove 25 in the plate 19, see Fig. 3. The lug 14 is then about to 25 enter into contact with the wedge-shaped lip 22, the further movement of plate 8 being downward in a vertical line which brings the lugs 14 and lips 22 into actual contact. A strong pull on lever 15 at this time brings 30 the lugs 14 and lips 22 into contact for their full length forcing the edge of the plate 8 deep into the groove 25 and straining the door, which is fastened to the plates 8, 8^a, 8^b, by the neck bolts 10, along its 35 vertical and bottom edges, toward the body of the car, and as these lugs 14 are placed at many points along the edges of the plates, the strain is such that close contact is secured with the car body, even if the door or 40 post be warped or bent. When the end of the lever is secured under the pin 23, the lugs 14 and lips 22 will maintain this strain, while the car is in transit, and as efficiently as if the door were bolted to the sides of the 45 car.

In the past, many leaks were caused by slight defects in the wooden posts and car door, these defects rendering it impossible to make close contact of the door with the 50 car body, but with the above-described construction, there is very little likelihood of a leak occurring, as the entry of the plates 8, 8^a, and 8^b into the grooves 25 is sufficient to not only form a grain-tight joint, but the 55 metal fittings above described for the edges and bottom of the door and for the face of the door post will prevent these parts from being chafed or splintered off.

The above-described doors are as applicable for use on steel cars as for wooden cars.

To prevent people from meddling with the lever when a loaded car is in transit, the clevis 27 is attached to the car in such a way as to turn up and receive the end of 65 the lever, and, the sealing pin 23 has a chain

attached to the eye at one end and to the car at the other, this pin projecting through the eye of the clevis, as shown, and having an elongated hole at its pointed end, suitable to receive a standard seal.

70

To release the car door, the lever 15 is moved from Y to Z, actuating the plates 8, 8^a, 8^b to free the wedge-shaped lugs 14 from the wedge-shaped lips 22. The door can then swing outward and thus be relieved 75 from the pressure of the load or obstacle against it, after which the door may be moved to its open position.

As the main car door may be constructed to abut against either the door post, or the 80 car body beyond the door posts, the term "car body" will be construed to include in its meaning those structural parts of the car other than the car door, and the parts movable with it.

85

Having thus fully described my invention, what I claim as new and desire to secure by Letters Patent is:

1. In a box car, the combination of a car body having a doorway therein, a sliding 90 door track secured to the car body, a car door to slide on said track and close or expose the doorway as the case may be, movable joint closing means along the bottom and both vertical edge faces of the door for 95 establishing a tight joint between the car door and car body, locking means carried by the joint closing means, and means co-operating therewith, secured to the car body for straining the car door toward the car 100 body.

2. In a box car, the combination of a car body having a doorway therein, a sliding door track secured to the car body, a car door to slide on said track and close or expose the doorway as the case may be, movable joint closing means along the bottom and both vertical edge faces of the door for 105 establishing a tight joint between the car door and car body, locking means carried 110 by the joint closing means, means co-operating therewith secured to the car body for straining the car door toward the car body, and means for actuating the joint closing means and the straining means.

115

3. In a box car, the combination of a car body having a doorway with grooves therein, a car door to close or expose the doorway, as the case may be, joint closing means movable across the edge faces of the 120 door to enter said grooves and establish a tight joint between the car body and the car door, means for making the joint closing means in this position rigid with the car door, locking mechanism comprising members carried by the joint closing means and other members secured to the car body, for straining the car door toward the car body and holding the car door in its closed 125 position.

130

4. In a box car, a car door having a joint closing plate movable across one of its edge faces into a position lapping the space between the door and the door post, and locking mechanism comprising members carried by said plate, and other members secured to the car body, to coöperate therewith for straining the car door toward the car body and holding it in its closed position.
- 10 5. In a box car, the combination of a car body having a doorway therein with grooves along its bottom and vertical edges, a sliding door track secured to the car body, a car door to slide on said track and close or expose the doorway as the case may be, a movable joint closing plate along the bottom and each vertical edge face of the car door to enter said grooves, locking mechanism comprising members actuated by the plates, and members for the car body co-operating with the members of said plates to strain the car door toward the car body and cause the plates to enter said grooves.
- 15 6. A car door for a box car comprising a joint closing plate movable across one of its edge faces to project beyond the inner face of the door and lap a projection of the door frame, and locking mechanism comprising members carried by said plate to operate with other members carried by the door frame and strain the car door toward the car body and hold it in its closed position.
- 20 7. In a box car, the combination of a car body having a doorway therein, stationary plates secured to the car body at the sides of the doorway, each plate having holes with a wedge-shaped lip projecting into each hole, a track secured to the car body, a car door to slide on said track, plates slidably secured to the car door to enter the holes in the stationary plates and engage with said wedge-shaped lips, and means for actuating the sliding plates, whereby the engagement of the wedge-shaped lips with the wedge-shaped lips will strain the door toward the car body, and cause the sliding plates to enter said grooves.
- 25 8. In a box car, the combination of a car body having a doorway therein, stationary plates secured to the car body at the sides of the doorway, each plate having a lengthwise groove and holes, with a wedge-shaped lip projecting into each hole, a track secured to the car body, a car door to slide on said track, plates slidably secured to the car door to enter the grooves in the stationary plates with wedge-shaped lips to enter the holes and engage with said wedge-shaped lips, means for actuating the sliding plates, whereby the engagement of the wedge-shaped lips with the wedge-shaped lips will strain the door toward the car body and cause the sliding plates to enter said grooves, comprising an operable lever and bell cranks pivoted to the car door, and links connecting the lever and bell cranks.
- 30 9. In a box car, the combination of a car body having a doorway therein, stationary plates secured to the car body at the sides of the doorway, each plate having holes with a wedge-shaped lip projecting into each hole, a track secured to the car body, a car door to slide on said track, plates slidably secured to the car door, having wedge-shaped lugs to enter the holes in the stationary plates and engage with said wedge-shaped lips, and means for actuating the sliding plates, whereby the engagement of the wedge-shaped lugs with the wedge-shaped lips will strain the door toward the car body, and cause the sliding plates to enter said grooves.
- 35 10. In a box car, the combination of a car body having a doorway therein, stationary plates secured to the car body at the sides of the doorway, each plate having a lengthwise groove and holes, with a wedge-shaped lip projecting into each hole, a track secured to the car body, a car door to slide on said track, plates slidably secured to the car door to enter the grooves in the stationary plates with wedge-shaped lips to enter the holes and engage with said wedge-shaped lips, means for actuating the sliding plates, whereby the engagement of the wedge-shaped lips with the wedge-shaped lips will strain the door toward the car body and cause the sliding plates to enter said grooves, comprising an operable lever and bell cranks pivoted to the car door, and links connecting the lever and bell cranks.
